CLAIM

The ornamental design for an electrical charger, as shown and described.

DESCRIPTION

This application is related to application Ser. No. 29/293,500, for Electrical Charger filed Nov. 28, 2007.

FIG. 1 is a perspective view of the front end of an electrical charger showing our new design;

FIG. 2 is perspective view of the back end thereof;

FIG. 3 is a right side view thereof, the left side being a mirror image;

FIG. 4 is a top plan view thereof, the bottom being a mirror image;

FIG. 5 is an end view of the back end thereof; and,

FIG. 6 is an end view of the front end thereof.
